UNITED STATES PATENT OFFICE.

PERCY F. RICE, OF TUSTIN, CALIFORNIA.

SELF-REPLENISHING FLUID POWER-TRANSMITTER.

No. 838,087.

Specification of Letters Patent.

Patented Oct. 9, 1906.

Application filed January 16, 1906. Serial No. 296,244

To all whom it may concern:

Be it known that I, PERCY F. RICE, a citizen of the United States, residing at Tustin, in the county of Orange and State of California, have invented a new and useful Self-Replenishing Fluid Power-Transmitter, of which the following is a specification.

This invention relates to flexible speed-transmitting devices in which the driving element operates the driven element through the medium of a confined fluid, the driven element rotating at equal speed with the driving element when the fluid is prevented from circulation and the driven element rotating at a variant speed from the driving element when the intermediate fluid is permitted to circulate, the ratio of movement between the driving and driven elements being dependent upon the rate at which the fluid is allowed to circulate. In a former application of mine, filed April 10, 1905, Serial No. 254,737, I have shown and described such a device; and the present invention consists of improvements in the specific construction shown in the former application, and it also includes means for replenishing the fluid. I have found in practice that when such a device is operated the fluid will escape very slowly, even if the device is well constructed and the parts fit perfectly, and while such escape of fluid is slight still when the device is to be used for a long period and is to be subjected to severe duty it is necessary to provide means for replenishing the fluid, so that the amount of fluid confined in the chambers will be a fixed quantity, for when an appreciable amount of fluid has escaped the operation of the device is impaired to an extent which, it is believed, would prohibit its practicability.

The main object of the present invention is to provide a simple and effective means for automatically replenishing the fluid, so that the device may be operated without requiring attention for a long period of time.

Other objects are to simplify and improve the specific construction of the device generally and particularly the valve shifting or controlling feature.

The accompanying drawings illustrate the invention.

Referring to the drawings, Figure 1 is a side elevation of the device with the valve-plate removed. Fig. 2 is a cross-section taken through the valve-plate and valve on

line $x^2 x^2$, Fig. 3. Fig. 3 is a horizontal diametrical section taken through the complete device. Fig. 4 is an enlarged section taken through the replenishing-pump, showing the same in detail.

The driving element comprises a shaft 1 in line with the driven element, which latter comprises a shaft 2. Rigidly mounted on the shaft 2 is a sleeve 3, into which the end of the shaft 1 projects, the sleeve forming a journal for maintaining good alignment of the two shafts. Formed on the sleeve 3 is a heart-shaped cam 4, the diametrical distance between opposite faces or points of the cam being the same—that is to say, all diameters of the cam are equal—the cam being of equal diametrical extension throughout, the diameters being taken as lines passing through the center of rotation of the cam and extending to the bearing-faces of the cam at each side. For example, the lengths of the dotted lines $a b c d e f$ are equal.

Rigidly mounted on the shaft 1 is a fly-wheel 5 with four cylinders 6 cast preferably integral therewith and projecting radially inwardly from the rim thereof. Mounted in each cylinder is a piston 7, having a roller 8, which bears against the face of the cam 4, each piston being provided with a piston-ring 9 and being cut away to form a recess 10. The fly-wheel 5 is provided with four ports 11, which communicate with the respective cylinders 6, as shown in Fig. 3.

A valve-plate 12 is bolted to the fly-wheel 5 and has a flanged hub 13, which is journaled on the sleeve 3. The valve-plate 12 has an outer boss 14, arranged eccentrically of but close to the hub 13, and the valve-plate 12 and boss 14 are bored to receive a valve 15. The valve 15 has an annular recess 16, and its outer shell is provided with four ports 17. The valve-plate 12 is provided with four passages 18, which radiate from the valve, each passage 18 terminating at a port 19, the respective ports 19 registering with the respective ports 11, formed in the fly-wheel 5. The valve 15 has a stem 20, which extends through a stuffing-box 21, the stem being rifled, having spiral grooves 22. A nut 23 is mounted on the rifled portion of the valve-stem 20 and is non-revolvable, being held from rotation by a guide-bracket 24, which projects out from the valve-plate 12, the nut 23 being grooved to engage the guide-bracket 24 and slide along the same when the nut is reciprocated.

The nut 23 is operated by a shift-sleeve 41, the nut engaging in a groove 25, formed in the sleeve. The sleeve 24 has another groove 26, which is engaged by a forked operating-lever 27. By swinging the lever 27 the sleeve 24 is pushed along the sleeve 3, thereby sliding the nut 23 along the guide-bracket 24, and the valve 15 is turned as the nut rides over the rifled valve-stem.

- 10 In order to replenish the liquid and keep the confining passages and cylinders full, I have provided an automatic self-governing pump. The rim of the fly-wheel 5 has a radial pocket 28, in which is screwed a tube 29, (shown in detail in Fig. 4,) having a perforated wall 30, formed with a seat to receive a ball-valve 31, the outward movement of the ball being limited by a pin 32. The tube 29 has a port 33, which communicates with the large 15 space within the fly-wheel 5. A piston 34 is arranged in the tube 29 and has two longitudinal slots 35, which receive the ends of a pin 36, which is carried by an eccentric-rod 37. A coil-spring 38 is arranged inside of the piston 34 to yieldingly hold the piston extended to the limit on the eccentric-rod 37. The eccentric-rod 37 has one end formed with a strap 37', which is mounted on an eccentric 39, formed on the sleeve 3 next to the cam 4. 20 The pocket 28 communicates with a passage 40, the latter communicating with one of the passages 18, as clearly shown in Fig. 2.
- The interior of the cylinders 6, passages 18, valve-space 16, passage 40, and the space 25 within the fly-wheel are filled with fluid, preferably oil, and when the valve 15 is turned into the position shown in Fig. 2 it prevents circulation of oil within the passages 18 and cylinders 6, and the pistons 7 are thus positively prevented from outward radial movement, as the shaft 1 is rotated, the rollers 8 of the pistons 7 are locked around the cam 4, and motion is thus imparted to the sleeve 3 and shaft 2, the parts of the device rotating 30 bodily as one mass with no relative movement between them, thus driving the shaft 2 at the same speed as shaft 1. By rocking the lever 27 sleeve 41 is moved along the sleeve 3, and the nut 23 is thus shifted along the rifled valve-stem 20, which turns the latter a degree corresponding to the amount the lever 27 is rocked, and when the valve is so turned as to bring its ports 17 partially into register with the passages 18 the oil within 35 the passages 18 and cylinders 6 is allowed to circulate, so that as the shaft 1 rotates motion is imparted to the heart-shaped cam 4 through the medium of the rollers 8 and pistons 7, the rate of movement of the cam 4 being dependent upon the speed at which the oil is permitted to circulate through the valve, thus driving the sleeve 3 and driven shaft 2 at a slower speed than the shaft 1. If the valve 15 is turned to bring its ports 17 40 into full perfect register with the passages 18,

free circulation of the oil is secured, so that no power or movement is imparted to the driven shaft 2 while the shaft 1 is rotated. When the valve 15 is adjusted to give relative movement between shafts 1 and 2, the piston 34 will be reciprocated by the eccentric 39, so that as the piston 34 moves toward the center of the fly-wheel and uncovers the port 33 in the tube 29 oil from the interior of the fly-wheel will pass through the port 33 into the tube 29, which passage of the oil is facilitated, as the centrifugal force imparted to the oil within the fly-wheel keeps the oil at the outer part of the fly-wheel next to the rim. As the piston 34 is moved forward by the eccentric 39 the oil within the tube 29 is forced through the perforated wall 30, past the ball-valve 31, and through the pocket 38 and passage 40 into the passage 18, thus replenishing the oil in the circulation. It is obvious that this pumping of the oil into the circulation occurs whenever there is a difference in speed between the shafts 1 and 2, and in order to prevent breakage of parts I have introduced the spring 38, which will yield when the circulating-passages are filled. The spring 38 is arranged to allow the piston 34 to yield or remain stationary during a full stroke of the eccentric 39. In this manner the oil is automatically replenished in the circulating-passages, and the latter are thus kept completely filled so long as there is surplus oil in the interior of the fly-wheel, and as the space in the latter affords a large reservoir capacity sufficient oil may be stored therein to enable the device to be run for an indefinite period. The oil which is stored within the fly-wheel also serves to lubricate all of the working parts of the device. 50

In order to balance the device, the valve-plate may have cast thereon a lug 42, arranged on the side of the axis opposite the valve.

The main leakage is from the cylinders into the interior of the fly-wheel, and as the latter is inclosed and acts as the supply-reservoir it is obvious that oil leaking from the cylinders is not lost, but used again and again. In this manner the oil is conserved.

On account of the general contour of the cam it has been termed "heart-shaped" for the sake of brevity, and it should be understood that its precise shape need not necessarily be exactly absolutely like the drawing; but it is essential that its diameters all be equal in length, and therefore in the claims such term refers to a cam having such diameters.

What I claim is—

1. A movable driving element, a driven element, a circulatory system for confining a liquid intermediate the two elements, means for maintaining a constant contact between the liquid and the driving and driven elements, a supply-reservoir adapted to receive the leakage from the circulatory system, and

- means for automatically replenishing the liquid in the circulatory system from the supply-reservoir.
2. A driving element, a driven element, a circulatory system for confining a liquid intermediate the two elements, means for allowing a variation in capacity of certain parts of the confining means but maintaining at the same time a constant capacity of the confining means as a whole, a supply-reservoir adapted to receive the leakage from the circulatory system, and means for automatically replenishing the liquid in the circulatory system from the supply-reservoir.
3. A driving element, a driven element, means for confining a liquid intermediate the two elements, means coöperating with the driving element for shifting the liquid when the driving element moves relatively to the driven element, adjustable means for retarding the shifting of the liquid, and positively-operating mechanism for automatically replenishing the liquid.
4. A driving element, a driven element, a cylinder carried by one of said elements, a cam carried by the other element, a piston in the cylinder for coöperating with the cam, means extraneous of the cylinder but communicating therewith for confining a liquid, means coöperating with the cam for maintaining a constant capacity of the confining means irrespective of the position of the piston, a supply-reservoir for receiving the leakage from the cylinder, and means for automatically transferring liquid from the supply-reservoir to the confining means and cylinder to maintain full quantity of liquid therein.
5. A driving element, a driven element, a cylinder carried by one of said elements, a cam carried by the other element, a piston in the cylinder for coöperating with the cam, means extraneous of the cylinder but communicating therewith for confining a liquid, means coöperating with the cam for maintaining a constant capacity of the confining means irrespective of the position of the piston, adjustable means for retarding the passage of the liquid through the confining means, and positively-operating mechanism for automatically supplying additional liquid to the confining means whereby the confining means is always kept full of liquid.
6. A movable driving element, a driven element, means for confining a liquid intermediate the two elements, means for maintaining a constant contact between the liquid and the driving and driven elements, and means for automatically replenishing the liquid comprising a pump-cylinder carried by one of said elements, a piston in the pump-cylinder operated by the other element, a reservoir for holding surplus oil, the pump-cylinder communicating with the reservoir and with the confining means whereby as the piston is operated by relative movement between the driving and driven elements, oil is pumped from the reservoir into the confining means.
7. A movable driving element, a driven element, a circulatory system for confining a liquid intermediate the two elements, means for maintaining a constant contact between the liquid and the driving and driven elements, a supply-reservoir for receiving leakage from the circulatory system, means for automatically replenishing the liquid, in the circulatory system from the supply-reservoir and means for automatically stopping the replenishing when the circulatory system is full of liquid.
8. A movable driving element, a driven element, means for confining a liquid intermediate the two elements, means for maintaining a constant contact between the liquid and the driving and driven elements, and a self-governing pump for automatically replenishing the liquid.
9. A driving element including a hollow fly-wheel, cylinders carried by the fly-wheel, pistons in the cylinders, a driven element, a cam therein coöperating with the pistons, a valve-plate on the fly-wheel, a valve in the valve-plate, the valve-plate having passages radiating from the valve to ports in the fly-wheel which communicate with the respective cylinders.
10. A driving element including a hollow fly-wheel, cylinders carried by the fly-wheel, pistons in the cylinders, a driven element, a cam therein coöperating with the pistons, a valve-plate on the fly-wheel, a valve in the valve-plate, the valve-plate having passages radiating from the valve to ports in the fly-wheel which communicate with the respective cylinders, the valve having a rifled stem, a non-revolvble nut on the stem, and means for sliding said nut on the stem to rotate the latter and adjust the valve.
11. A driving element including a hollow fly-wheel, cylinders carried by the fly-wheel, pistons in the cylinders, a driven element, a cam therein coöperating with the pistons, a valve-plate on the fly-wheel, a valve in the valve-plate, the valve-plate having passages radiating from the valve to ports in the fly-wheel which communicate with the respective cylinders, the valve having a rifled stem, a non-revolvble nut on the stem, a loose sleeve on the driven element engaging the nut for sliding the same, and a lever for shifting the sleeve.
12. A driven element including a hollow fly-wheel, cylinders carried by the fly-wheel, pistons in the cylinders, a driven element, a cam therein coöperating with the pistons, a valve-plate on the fly-wheel, a valve in the valve-plate, the valve-plate having passages radiating from the valve to ports in the fly-wheel which communicate with the respective

- tive cylinders, a pump-cylinder carried by the fly-wheel, the pump-cylinder having an inlet communicating with the interior space of the fly-wheel, and having an outlet which 5 communicates with a passage leading to one of the said passages in the valve-plates, a piston in the pump-cylinder, an eccentric on the driven element, and a connection from the eccentric to the piston.
10. 13. A driving element including a hollow fly-wheel, cylinders carried by the fly-wheel, pistons in the cylinders, a driven element, a cam therein cooperating with the pistons, a valve-plate on the fly-wheel, a valve in the 15 valve-plate, the valve-plate having passages radiating from the valve to ports in the fly-wheel which communicate with the respective cylinders, a pump-cylinder carried by the fly-wheel, the pump-cylinder having an 20 inlet communicating with the interior space of the fly-wheel, and having an outlet which communicates with a passage leading to one of the said passages in the valve-plates, a piston 25 in the pump-cylinder, an eccentric on the driven element, and a connection from the eccentric to the piston, the latter piston being yieldingly carried by said connection, and a check-valve for preventing escape of liquid from the valve-plate passages through the 30 pump.
14. A driving-shaft, a driven shaft, a hol-

low fly-wheel carried by the driving-shaft, a sleeve fastened to the driven shaft and receiving the driving-shaft, a valve-plate fastened to the driving-shaft and having a hub 35 journaled on the sleeve, cylinders carried by the fly-wheel and communicating with radiating passages formed in the valve-plate, a cam on said sleeve, pistons in the cylinders having rollers which bear against the cam, a 40 valve in the valve-plate for controlling the circulation of liquid through the passages in the valve-plate, the valve having a rifled stem, a non-revolvable nut on the stem; a shift-sleeve on the first-mentioned sleeve and 45 having a groove which engages the nut, a forked lever engaging another groove in the shift-sleeve for operating it, a pump carried by the driving element, an eccentric on the first-named sleeve adjacent the cam, and a 50 connection from the eccentric to the pump for operating the same when relative movement occurs between the driving and driven elements.

In testimony whereof I have hereunto set 55 my hand, at Los Angeles, California, this 9th day of January, 1906.

PERCY F. RICE,

In presence of—

GEORGE T. HACKLEY,
VERNA A. TALBERT.
